FORM LIFTER FOR BOX WRAPPING MECHANISM

Ernest G. Rider, Philadelphia, Pa., assignor to Stokes and Smith Company, Summerville, Pa., a corporation of Pennsylvania

Application April 13, 1940, Serial No. 329,487

3 Claims. (Cl. 93—54.2)

The present invention relates to box wrapping mechanism and more particularly to an attachment for assisting an operator in separating the forming blocks.

During the operation of wiping and folding a wrapper about a box it happens more or less frequently that portions of the wrapper adhere to the form blocks and obstruct proper operation of the machine until this material is scraped from the blocks. To remove this material the operator must support the upper form block with one hand while attempting to scrape in the small space between the blocks. This is an awkward and inefficient method and results in an appreciable loss of time in machine hours.

Some of the objects of the present invention are to provide a novel attachment for box wrapping machines whereby easy access can be had to the working faces of the forming blocks; to provide means wherein provision is made for supporting the upper forming block of a box wrapping machine to allow an operator to use both hands in cleaning the forming blocks; to provide a supporting device for the upper block of a box wrapping machine which automatically becomes ineffective when the wrapping machine resumes operation after a stoppage; and to provide other improvements as will hereinafter appear.

In the accompanying drawing forming part of this description:

Fig. 1 represents a front elevation partly broken away of a portion of a box wrapping mechanism as equipped with one form of the present invention and showing the forming blocks in closed position;

Fig. 2 represents the same elevation showing the open position of the blocks after the device of the invention has been operated;

Fig. 3 represents a section on line 3—3 of Fig. 4;

Fig. 4 represents a section on line 4—4 of Fig. 1; and

Fig. 5 represents a detail of the lift cam.

Referring to the drawing, one form of the present invention as applied to a box wrapping machine of the general type shown in Letters Patent No. 691,329 wherein an upper form block 10 is suspended by side rods 11 in vertical alignment with a lower main former 12 which is carried by a tubular plunger 13 and spur 14. The rods 11 and plunger 13 are arranged for vertical movement independent of each other and have related cycles of operation determined by separate cam or other mechanisms to carry out the required function. During the wrapping opera-

tions the form block 10 rises as necessary to permit certain turn-in fingers to pass above the main former 12 and fold the upstanding ends and sides of the wrapper material into position to be wiped into the box by the lowering of the form block 10 on its return stroke. This wiping and pressing action of the form block 10 frequently results in some of the wrapping material adhering to the block and this necessitates stopping the machine, raising the block 10 by hand and holding it up while the other hand of the operator scrapes and frees the block of the material. It is to this troublesome operation that the present invention is directed to result in greater simplified action and a maximum reduction of idle machine hours.

In order to lift the form block 10 and its associated assembly independently of the normal power actuated means, a lift bar 15, preferably 20 of flat bar stock, is provided having attached thereto at one end an offset tubular sleeve 16 which is fitted over one of the lift rods 11 and fixed thereto by a friction ring 17 encircling the rod 11 and seating laterally in a circumferential 25 groove 18 cut in the rod 11 in close proximity to a shoulder 20 formed by an enlargement of the diameter of the bore of the sleeve 16. The bar 15 is disposed vertically edgewise and is long enough to extend from the rod 11 through the 30 plunger 13 where it is guided by oppositely disposed guide slots 21 cut vertically in the respective opposite sides of the aforesaid plunger. These slots 18 are sufficiently longer than the width of the bar 15 to allow the proper relative 35 motion of the rods 11 and plunger 13 when these parts are under control of the operating cams or other means. The fixed position of the lift bar 15 and the location of the slots 21 is such as not to interfere with or prevent any normal 40 movements of the two forming blocks.

For the purpose of elevating the lift bar 15 a cam 22 is eccentrically carried on the end of a rock spindle 23 which is journalled in a bearing bushing 24 fixed to and passing through one 45 side of the plunger 13. A collar 25 abuts the plate 26, which anchors the bushing 24 in place, and is fastened to the spindle 23 by a set screw 27 to maintain the proper relation of the parts. An operating lever in the form of a hub 28 and 50 two diametrically opposite arms 29 and 30, is fixed to the spindle 23 by a pin 31 or other fastening means to rock the spindle from one position to the other. Normally the cam 22 is in the position shown in Fig. 1 and in order that 55 it return automatically when the machine re-

sumes operation, a counterweight is provided for the purpose. As shown this counterweight consists in making the lower arm 30 of the lever longer than the alined upper arm 29 and therefore when the heavier arm 30 is in its upper position and the machine shifts the plunger 13 to thereby release the cam, then gravity returns the lever to its normal position with the cam in its lower position. Preferably that face of the cam 22 which is furthest from the axis of rotation is formed with a seat 32 having sufficient area to abut the edge face of the lift bar 15 with just enough resistance to prevent slight jars from prematurely releasing the lift bar 15 when in the position shown in Fig. 2.

The device is brought into operation whenever there is a clogging of the form blocks due to a wrapper jam. When this happens the machine is stopped, the operator grasps the lever and turns it through one hundred and eighty degrees. This movement swings the cam 22 upwardly to also lift the bar 15 and through it the rods 11 and upper form block 10 so that sufficient space is opened between the form blocks to permit proper access in order to remove jammed or stuck wrapping material. This operation can be carried out efficiently because both hands of the operator are free to correct the trouble since the cam 22 is in its uppermost position holding the lift bar 15 seated thereon. As soon as the blocks are cleared, ready to resume operations, the machine is started whereupon the incident vibration shakes the counterweight arm 30 from dead center position and thus swings the lever and cam 22 back to normal position.

While only a single form is shown in which this invention may be embodied, it is to be understood that the invention is not limited to any specific construction, but might be applied to 40

various forms without departing from the spirit of the invention or the scope of the appended claims.

I claim as my invention:

- 5 1. In a mechanism for applying wrappers to boxes, the combination of an upper forming block, operating means for said block, a main forming block, a laterally disposed bar fixed to said operating means, a cam having a flattened surface arranged, when turned, to engage and lift said bar to elevate and temporarily lock said upper block from said main block, and means to actuate said cam.
- 10 2. In a mechanism for applying wrappers to boxes, the combination of an upper forming block, operating means for said block, a main forming block, a laterally disposed bar fixed to said operating means, a cam arranged, when turned, to engage and lift said bar to elevate said upper block from said main block, means to actuate said cam, and means comprising a substantially flattened area on said cam to support and temporarily to lock said bar in elevated position.
- 15 3. In a mechanism for applying wrappers to boxes, the combination of an upper forming block, operating means for said block, a main forming block, a laterally disposed bar fixed to said operating means, a cam arranged, when turned, to engage and lift said bar to elevate said upper block from said main block, and means including a two arm lever to actuate said cam, one arm of said lever being heavier than the other, said cam comprising a relatively flat area to support and temporarily to lock said bar in elevated position and arranged for automatic unlocking when the motion of the mechanism moves the bar from contact with said flat area of said cam.

ERNEST G. RIDER.
